UNITED STATES PATENT OFFICE

117,406

DESIGN FOR A COMBINED DIGESTING AND DISTILLING APPARATUS

Alexander I. Newman, Chicago, Ill., assignor to Precision Scientific Company, Chicago, Ill., a corporation of Illinois

Application July 20, 1939, Serial No. 86,116

Term of patent 7 years

To all whom it may concern:

Be it known that I, Alexander I. Newman, a citizen of the United States, residing at Chicago, in the county of Cook and State of Illinois, have invented a new, original, and ornamental Design for a Combined Digesting and Distilling Apparatus, of which the following is a specification, reference being had to the accompanying drawing, forming part thereof.

Fig. 1 is a front perspective view of a combined

digesting and distilling apparatus embodying my new design.

Fig. 2 is a rear elevational view of the same on a slightly smaller scale.

I claim:

The ornamental design for a combined digesting and distilling apparatus, substantially as shown.

ALEXANDER I. NEWMAN.
